UNITED STATES PATENT OFFICE.

FRANCIS A. GOODROW, OF ELGIN, ILLINOIS, ASSIGNOR TO ELGIN NATIONAL WATCH COMPANY, OF ELGIN, ILLINOIS, A CORPORATION OF ILLINOIS.

DESIGN FOR A WATCH-DIAL.

56,424.

Specification for Design.

Patented Oct. 26, 1920.

Application filed March 6, 1920. Serial No. 363,840. Term of patent 14 years.

To all whom it may concern:

Be it known that I, FRANCIS A. GOODROW, a citizen of the United States, residing at Elgin, in the county of Kane, State of Illinois, have invented a certain new, original, and ornamental Design for Watch-Dials, of which the following is a description, reference being had to the accompanying drawing, forming a part thereof.

The figure is a plan view of a watch dial, showing my new design.

This design comprises the annular portion upon the outer face of which is the green bordered design illustrated. Within this outer green border is the white metal annular portion upon which are arranged the Roman numerals of the configuration and with the ornamentation shown. In-

serted within a portion of the periphery at the lower face, is the seconds disk and in the wide crescent space between the upper half of the seconds disk and the inner rim of the annulus is the ornamental scroll work and conventional flower work shown in green upon a contrasting background of gold color.

I claim:

The ornamental design for a watch dial, as shown.

In testimony whereof, I affix my signature in the presence of three witnesses.

FRANCIS A. GOODROW.
